UNITED STATES PATENT OFFICE.

CHESTER F. SMITH, OF TORRINGTON, CONNECTICUT.

TOY PISTOL.

Specification forming part of Letters Patent No. 98,611, dated January 4, 1870.

To all whom it may concern:

Be it known that I, CHESTER F. SMITH, of Torrington, in the county of Litchfield and State of Connecticut, have invented a new and useful Improvement in Self-Loading Toy Pistols; and I do hereby declare that the following is a full, clear, and exact description thereof, which will enable others skilled in the art to make and use the same, reference being had to the accompanying drawings, forming part of this specification.

The invention relates to toy pistols; and it consists in a certain novel construction and arrangement of parts, to be hereinafter more particularly specified.

Figure 1 is a longitudinal section of my improved toy pistol, and Fig. 2 is a transverse section of the same.

Similar letters of reference indicate corresponding parts.

A is the barrel, and B the magazine. The latter is arranged above the former and receives the balls at the breech through the well C, opening down from the top. This well continues down through the magazine and communicates with the barrel, which extends rearward slightly beyond the well, and has fixed at the bottom a coiled spring, D, carrying a plug, E, at its front end, having a pin, E, extending through it transversely and through slots F in the sides of the barrel. The ends, at a short distance from the barrel, are provided with thumb-bits G.

H is the catch-trigger, pointed at I to the stock, and provided with two catches, K, rising up at the sides of the barrel and engaging the pin E inside the thumb-bits when the spring is retracted to hold it. The said catch-trigger is also provided with a catch, L, in advance of the said catches K, and at the center of the under side of the barrel, working up through a slot therein in advance of the ball when the said catches K are holding the spring back to prevent the ball from rolling away from the spring previous to discharging. The rear curved end, H', of the trigger is provided with a spring, N, bearing against the stock and forcing catches K and L upward to hold the spring D back, which is disengaged by pulling the catch-trigger back against the said spring N and forcing it backward. It is held in place by being set into a circular recess in the stock.

O represents the plate on the top of the magazine at the breech for supporting the

usual vertical notched sighting-plate, P. For the purpose of utilizing this plate as the cover of the supply-well C, I have pivoted it at Q and extended it forward sufficiently for the purpose, as shown in Fig. 1, and thereby furnish the two devices cheaper than if made and attached separately. In like manner I arrange the pin R at the nozzle, which is drawn in to form the sight thereat to serve as a stop to prevent the escape of the balls and save the expense of plugging the end of the magazine, which is formed by boring from that end.

It will be seen that by raising the nozzle of the gun the balls will roll to the rear and drop into the well, falling upon the spring, if extended, and into the barrel behind the catch L, and in front of the spring, if the latter is retracted; also, that the discharge of the spring will eject only the ball in front of it, the said spring passing under the one in the well above the one in front. The pistol is therefore self-loading, the magazine being charged with one or more balls, and to shoot the balls requires only the retracting and discharging of the spring. The former is done by taking the thumb-bits between the thumb and finger and pulling back until the pin is engaged by the catch.

The balls may be supplied to the magazine through openings at other places, and the magazine may be placed on the side of the barrel; but I prefer the arrangement which I have shown.

Other arrangements of the plug E and pin F with the spring may be made; and I do not confine myself to the precise arrangement shown.

I prefer to make the magazine, barrel, and stock of wood; but they may be made of other suitable substance.

Having thus described my invention, I claim as new and desire to secure by Letters Patent—

The combination, with the spring and the barrel, of the stud-pin E and catch-trigger, arranged for holding the spring and the ball and for disengaging them, all substantially as specified.

The above specification of my invention signed by me this 9th day of November, 1869.

CHESTER F. SMITH.
